UNITED STATES PATENT OFFICE

2,436,898

PLUNGER SWITCH

Ernst Walter Rickmeyer, Elmhurst, Ill., assignor
to Jefferson Electric Company, Bellwood, Ill., a
corporation of Illinois

Application January 20, 1945, Serial No. 573,656

2 Claims. (Cl. 200—159)

1

This invention relates to an improved construction for plunger type switches.

That particular embodiment of my invention herein shown and described is directed to a plunger type switch which is biased into closed circuit position, this type of switch being commonly used in connection with doors, such as refrigerator doors, automobile doors, and the like, wherein it is desired to automatically close the light switch when the door is open.

My invention relates specifically to a novel and improved arrangement of parts such that a metal housing may be used for the switch, the current carrying parts being insulated from the housing and from each other.

It is an object of this invention to provide an improved switch construction in which the parts are fully insulated.

It is a further object to provide an improved construction for a spring biased plunger switch which may be manufactured at low cost, and which is easy to assemble.

Another object is to provide an improved switch construction which is mounted in a metal housing which embodies means for carrying a slideable plunger, together with a spring for biasing the plunger into closed circuit position.

Still another object of my invention is to provide novel means for mounting the contact members of a switch in a spaced position so that they may be engaged by a bridge member carried by a suitable plunger.

Other objects, features and advantages of my invention will appear as the description proceeds.

With reference now to the drawings, which illustrate a preferred embodiment of my invention, and in which like reference numerals designate like parts—

Fig. 1 is a sectional elevation of a plunger type switch;

Fig. 2 is a section taken along line 2—2 of Fig. 1;

Fig. 3 is a section taken along line 3—3 of Fig. 1;

Fig. 4 is a detail of the contact mounting member;

Fig. 5 is a detail of the contact bridging member; and

Fig. 6 illustrates a modified form of construction for the insulating lining.

The switch comprises a metal shell 10 which forms a housing, together with a reciprocating plunger 13 which extends through the top wall of the shell and is adapted to be depressed in order to break the circuit through the switch.

2

The shell 10 has an opening for the plunger, in which opening is disposed a collar 11, the collar having a downwardly projecting skirt which is spun around the edge of the opening in the shell, as indicated by reference numeral 12. The collar is of sufficient length so that the plunger is substantially free from lateral movement; that is, the plunger does not wobble in the collar.

The open end of shell 10 is closed by a base member 14 formed of suitable insulating material, such as a phenolic condensation product, either laminated or molded or, fiber. The side walls of the shell 10 have downwardly depending lugs 15 which are bent over on to the base 14 to hold it in position.

The plunger 13 is provided with a flange 16 which engages the shell 10 to limit its upward motion. A contact bridging member 17, made of a suitable conductor, is secured to the under side of flange 16. The plunger 13 includes a depending portion of reduced diameter which is surrounded by a spring 19. The lower end of spring 19 is received in a cup 20, the position of the latter being determined by an embossing 21 formed in the base 14.

It will be seen that the cup 20 and the depending portion 18 confine the ends of the spring, and prevent any lateral displacement thereof which might lead to a short circuiting of the parts.

L-shaped contact strips 22 and 23 are disposed within the shell 10, the ends of each extending through suitable slots in the base 14. The upper ends of the contact strips are provided with contact points 24 and 25, respectively, which extend downwardly into such a position that they may be engaged by the contact bridging member 17 when the plunger 13 is in its uppermost position.

The contact strips 22 and 23 are insulated from the interior surface of the shell 10 by an insulating lining. This lining is preferably made up of a plurality of sheets of insulating material, such as vulcanized fiber, and includes an apertured sheet 26 for the top of the shell, sheets 27 and 28 for the end walls thereof, and sheets 29 and 30 for the side walls thereof. Thus the interior of the shell is completely lined with insulating material, and the contact strips 22 and 23 are separated from the shell by such insulating material.

An alternative form in which the lining may be constructed is shown in Fig. 6, wherein the insulating members 27', 28', 29' and 30' are formed in an integral sheet 38 which may be folded along the fold lines 39 which separate the various portions.

The upper portions of the contact strips 22 and 23 are mounted in a contact mounting member 31. As shown in Figs. 1 and 4, the mounting member 31 is provided with two recessed portions 32 in which recessed portions are formed slots 33 and circular apertures 34. The vertical portions of the contact strips 22 and 23 extend through the slots 33 and are held thereby in spaced relationship. The contact points 24 and 25 extend downwardly through the circular apertures 34 so that they may be engaged by the contact bridging member 17 to close the circuit.

The lower ends of the contact members 22 and 23 are held in spaced position by the apertured base 14. The contact strips are also provided with inwardly extending tongues 40 and 41 which abut against the base member 14, thereby preventing any vertical movement of the contact strips. Thus the contact strips are maintained in spaced position both at their upper and lower ends, and the cooperation between the contact points 24 and 25 and the circular apertures 34 effectively serves to prevent any twisting of the contact members in the slots 33.

Contact bridging member 17 is provided with side extensions 35, the edges of which are curled as indicated by reference numeral 36 so as to provide a low friction sliding contact with the lining sections 29 and 30. These side extensions 35 also tend to prevent any lateral motion or wobble of the plunger 13. The contact bridging member 17 also embodies end portions 37 which contact the contact points 24 and 25. The operation of the switch has been pointed out above in connection with the description of the various parts thereof.

One of the main advantages of this switch is the ease with which it may be assembled. After the collar 11 has been spun onto the shell 10, the insulating portion 26 is inserted, and then the contact spacer member 31 into which the contact strips 22 and 23 have already been placed. Then the liner portions 27, 28, 29 and 30 are inserted, and the plunger and contact bridging member assembly are inserted. The spring 19, the cup 20 and the insulating base 14 are then placed in position, and the lugs 15 are bent over the latter, thereby completing the assembly.

Although only a preferred form of this invention has been shown and described herein, it is apparent that many modifications and changes may be made therein without departing from the spirit of the invention.

I claim:

1. A plunger type switch comprising a metal housing having a closed top, a base therefor, an insulating lining for said housing, a plunger extending through said top, means to bias said plunger upwardly, a bridging member carried by said plunger, contact members adapted to be engaged by said bridging member when said plunger is in its extended position, L-shaped conducting strips having vertically extending portions disposed along said insulating lining and extending through said base member and having horizontally extending portions on which said contact members are carried, and a contact mounting member at the top of said housing provided with apertures through which said strips and contact members extend for maintaining said strips and contact members in spaced positions at opposite sides of said plunger, said horizontally disposed portion being confined between the upper surface of said contact mounting member and the insulating lining adjacent the closed top of said housing.

2. A plunger type switch comprising a metal housing having a top wall, a base therefor, an insulating lining for the side walls of said housing, a plunger extending through said top wall, means to bias said plunger upwardly, a contact engaging member carried by said plunger, contact members adapted to be engaged by said contact engaging member when said plunger is in its extended position, and a contact mounting member at the top of said housing provided with apertures through which said contact members extend for maintaining said contact members in spaced positions at opposite sides of said plunger, said contact mounting member being confined between the upper edges of said insulating lining and the top of said housing.

ERNST WALTER RICKMEYER.
